FILM HOLDING APPLIANCE

Charles S. Bassin, Newton, Mass., assignor to New England Theatres, Inc., Boston, Mass., a corporation of Delaware

Application June 28, 1939, Serial No. 281,566

8 Claims. (Cl. 95—100)

This invention pertains to the art of photography and relates more particularly to an appliance for holding a cut film or the like during the various stages of the developing process. While primarily intended for use for holding cut film, it is not necessarily limited to such use but might, if desired, be employed for holding other sensitized and exposed sheet-like elements, for instance, paper prints.

While tank development of films and plates is widely practiced, a very considerable number of photographers, both professional and amateur, still prefer tray development, since it permits individual treatment of each exposure and in skilled hands is conducive to better and more artistic effects. However, developing, fixing and washing, in accordance with tray development, require several handlings of the sensitized element with concomitant danger of fingerprinting, scratching or otherwise damaging the coatings. The difficulty is especially pronounced in handling a thin flexible element such as a cut film which, when wet, is slippery and tends to adhere to the bottom of the tray. Furthermore, the use of the fingers for transferring the film from one treating bath to another is a common source of staining and of contamination of the developing solution.

The present invention provides an appliance or holder designed to hold cut film or the like substantially flat and so that it may readily be immersed in a shallow body of solution. The holder has a handle for manipulating it so that the user need not wet his fingers in any of the solutions used, although he may readily move the sensitized element about within the solution or may transfer it from one bath to another.

In accordance with the present invention, the holder is so constructed as to be substantially devoid of cracks or crevices and has a smooth surface so that it is very easy to rinse off any of the several solutions into which it may be dipped. Furthermore, the device is very simple in form and cheap to construct and thus it becomes feasible for the user to provide himself with such a number of holders that an individual holder may be assigned to each film of the batch to be developed. The film may thus remain in its holder during the several successive stages of development and during the final drying. The damage of contamination of the developing solution is thereby greatly lessened. Furthermore, by proceeding in this way it is unnecessary to touch the film at all with the hand during the entire

process, the film being so held as to avoid damage to its sensitized surface and being kept flat until it is completed and dried.

In the accompanying drawing wherein certain desirable embodiments of the invention are illustrated by way of example,

Fig. 1 is a top plan view of the appliance, shown as having a film mounted therein, the film being indicated by broken lines;

10 Fig. 2 is a side elevation of the appliance of Fig. 1,—a conventional developing tray being indicated in broken lines;

Fig. 3 is a bottom plan view of the appliance, the handle being broken away;

15 Fig. 4 is a section on the line 4—4 of Fig. 1, to somewhat larger scale;

Fig. 5 is a fragmentary section on the line 5—5 of Fig. 1, to larger scale, illustrating the mode of mounting the film in the appliance; and

20 Fig. 6 is a fragmentary plan view illustrating a modified construction.

Referring to the drawing, the appliance is shown as comprising the film-holding portion 1 and the handle 2. The portion 1 preferably consists of a single length of stiff and substantially rigid wire of a character such that it will not readily be corroded by the solutions in which the device may be placed. Stainless steel wire is 25 recommended for the purpose, although other corrosion-resistant metals or metals coated or plated with corrosion-resistant materials may be employed, for example, brass wire coated with rubber or a suitable synthetic resin. The handle 2 also preferably consists of a single piece of 30 wire, or, as hereinafter more fully described, the entire device, including the holding portion and handle, may consist of a single integral length of wire. Wire of the order of $\frac{3}{16}$ inch diameter is 35 quite desirable, as it is readily possible to obtain wire of that diameter which is stiff enough for the purpose and, on the other hand, wire of that size does not elevate the film too high from the bottom of the tank. The film-holding portion of 40 the appliance is preferably of substantially rectangular contour, although it is contemplated that it may be of a different contour, for example, substantially triangular, and still embody the broader principles of the invention.

45 As illustrated, the wire which forms the holding portion 1 is so bent as to provide four supporting elements which are disposed in substantially the same plane and which are designed to underlie the marginal portions of the film F at its respective edges a, b, c and d.

The supporting element which underlies the margin adjacent to the edge *a* of the film comprises the elongate substantially rectangular part 3 (Fig. 3) designed to extend parallel to the edge *a* of the film, and the relatively short parallel legs 4 and 5 which extend outwardly from the respective ends of the part 3 and which are substantially perpendicular to the edge *a* of the film.

The supporting element which underlies the margin of the film adjacent to the edge *c* comprises the elongate part 6 designed to extend substantially parallel to the edge *c*, and the relatively short parallel legs 7 and 8 projecting outwardly from the respective ends of the part 6 and which are substantially perpendicular to the edge *c* of the film.

The supporting element which underlies the margin of the film adjacent to the edge *d* comprises the elongate part 9 and the parallel legs 10 and 11 which extend outwardly from the respective ends of the part 9 and which are substantially perpendicular to the edge *d* of the film.

The supporting element which underlies the margin of the film adjacent to the edge *b* comprises the elongate part 12 designed to extend parallel to the edge *b* and the relatively short parallel legs 13 and 14 which extend outwardly from the ends of the part 12 and which are substantially perpendicular to the edge *b* of the film.

The holding portion of the device also comprises retaining elements which are designed to overlie the respective corners of the film, each of said retaining elements consisting of a portion of the wire bent substantially to L-shape. The retaining element which overlies the corner of the film where the edges *c* and *d* intersect comprises the leg 15 substantially perpendicular to the edge *c* and the leg 16 which is substantially perpendicular to the edge *d*.

A second retaining element comprises the leg 17 which is substantially perpendicular to the edge *d* and the leg 18 which is substantially perpendicular to the edge *a*.

The third retaining element comprises the leg 19 which is substantially perpendicular to the edge *c* and the leg 20 which is substantially perpendicular to the leg *b*.

The fourth retaining element comprises the leg 22 which is substantially perpendicular to the edge *b* and the leg 21 which is substantially perpendicular to the edge *a*. Preferably the legs 20 and 22 are longer than the legs 16 and 17.

The four retaining elements are disposed in a plane which is so vertically spaced from the plane of the supporting elements as to permit the introduction of the film between said planes.

The several legs of the retaining elements are united to corresponding legs of the supporting elements by smoothly curved bights of the wire constituting film-positioning means. Thus, for example, the legs 17 and 10 are united by the bight 23; the legs 22 and 13 by the bight 24; the legs 18 and 4 by the bight 25; and the legs 15 and 7 by the bight 26, etc., the several bights of wire being curved in vertical planes with the concavely curved surface facing inwardly for engagement with the edge of the film.

It will be observed that at each side of the substantially rectangular open frame constituting the holding portion of the appliance there are two of these curved pocket-forming bights of wire. As noted, these bights have curved in-

ner surfaces which are designed to embrace and to engage the respective edges of the film. Preferably the several pockets *P*, each formed by one of these curved bights, are so spaced and related that the edge of the film engages the concavely curved walls of the pockets with a slight degree of pressure such that the curvature of the wall tends to hold the film substantially midway between the supporting and retaining elements. However, although such positioning of the film is desirable, since any contact whatever of the coated surface of the film with parts of the holder is thereby avoided, it will be understood that if the film be of slightly less dimensions than that for which the holding portion is designed, the uncoated surface of the film may rest upon the supporting elements and that under ordinary conditions the coated surface will not engage the retaining elements, and that if it does so contact the retaining elements, the contact is confined to the corner portions of the film.

By making the legs 20 and 22 longer than the legs 16 and 17, the pockets *P* at the right-hand end of the holder, as illustrated, are somewhat deeper than the pockets at the opposite end. In placing the film in the holder, one edge is slipped into the deeper pockets, as illustrated in Fig. 5; the film is then buckled upwardly to a slight extent so that its opposite edge may slip beneath the member 9; and when the film is released it straightens out with its respective edges seated in the several pockets.

The handle 2, as illustrated in Figs. 1 to 5 inclusive, comprises a length of wire twisted so as to form a looplike horizontal grip portion 28, a vertical or offset portion 28, and substantially horizontal divergent parts 27 whose ends are soldered, brazed or welded to the part 12. The vertical height of the member 28 is such that when the holding portion rests upon the bottom of the tray *T*, the hand grip portion 29 of the appliance will be above the plane of the top edge of the tray. Thus the user may subject a film mounted in the holding portion of the appliance to the action of the requisite solutions or baths without wetting his hand with the fluid.

In Fig. 6 a slight modification is illustrated wherein the handle portion and the film-holding portion consist of a single integral length of wire which is twisted to form the grip portion 29^a, and which is bent to provide an upright or offset portion and the horizontal members 27^a. The parts 27^a merge integrally with parts 12^a, 20^a corresponding to the single part 12 of the previously described embodiment, the remainder of the holding portion being exactly like that above described. The ends of the single length of wire may be united at any convenient point and in any desired manner.

In using the device, the film may be mounted in the holding portion 1, as above described, and subjected to the action of the developing solution in the tray *T* until development is complete. Then, without removing the film from the appliance, the film may be washed, fixed, rewashed, and dried, the loop-like handle constituting convenient means by which the appliance may be suspended while the film is drying. During the drying, the film is held substantially straight and flat by the retaining and supporting elements and out of contact with anything which might injure the coating.

While it is preferable to leave the film in the appliance throughout the entire process, it is

obvious that the film may be removed at any desired stage and that the appliance may be used for subjecting one film after another to any single treatment comprised in the process of development. It is further to be understood that the appliance may be used for holding other sensitized elements, for example paper prints or the like, while development takes place.

Moreover, while the device is preferably of rigid, unitary character in order to reduce its cost and to facilitate cleansing and is designed for use with a flexible film, which may be bent in order to introduce it into the holding portion of the appliance, it is to be understood that it may be used for holding a more or less rigid element such as a photographic plate, if the latter be of proper dimensions to permit its introduction beneath the retaining elements.

While desirable embodiments of the invention are herein illustrated and described by way of example, it is to be understood that the invention is not necessarily limited to these precise embodiments, but is to be regarded as broadly inclusive of any and all equivalent constructions such as fall within the terms of the appended claims.

I claim:

1. An appliance of the class described and designed for use in the tray development of cut film, said appliance comprising a film-holding portion including parts which underlie and overlie the marginal portions only of the film and which are constructed and arranged to hold the film in a substantially horizontal plane close to the bottom of the tray, and a handle having a grip portion disposed in a plane above that of the top of the tray, the film-holding portion being devoid of crevices or acute angles and consisting of a single length of smooth and substantially rigid corrosion-resistant wire having rounded bights constituting pockets for the reception of the respective edges of the film.

2. An appliance of the class described comprising a length of wire having elongate film-supporting portions arranged respectively to underlie the four margins of a rectangular piece of film, said elongate portions being in substantially the same plane, the wire also including film-retaining portions arranged to overlie the film at its four corners respectively, the wire also having bights curved in vertical planes and which unite the elongate supporting portions to the adjacent retaining portions, said bights constituting pockets for the reception of the respective edges of the film.

3. An appliance for use in the tray development of cut film or the like, said appliance comprising a length of wire bent to provide four pairs of curved bights, the several bights being so disposed and arranged that each pair of bights receives one of the respective edges of the film, elongate supporting elements integral with said bights and arranged to underlie the respective margins of the film, and a handle secured to one of said elongate supporting elements and comprising a substantially vertical portion of a height exceeding the depth of the tray, and a grip portion united to the upper end of said vertical portion.

4. An appliance for use in the tray development of cut film comprising a film-holding por-

tion and a handle, the holding portion including supporting elements disposed in a horizontal plane and arranged to underlie the margins of the film, the vertical thickness of said supporting elements being of the order of $\frac{1}{2}$ inch, the holding portion also including positioning elements engageable with the respective edge of the film to prevent it from shifting horizontally, the handle including a grip portion disposed in a plane so vertically spaced from the plane of the supporting elements that the hand of the user need not enter the tray.

5. An appliance of the class described comprising a film-holding portion and a handle, the film-holding portion consisting of a length of wire arranged to form four supporting elements, each having an elongate part designed to extend substantially parallel to one edge respectively of the film, and a pair of parallel legs disposed at right angles to said edge, the elongate parts of the supporting elements defining the four sides of an open rectangular frame and being designed to underlie the respective margins of the film, the wire also forming four film-retaining elements each of substantially L-shape and arranged to overlie the respective corners of the film, each leg of each L-shaped element being connected respectively by a curved bight of the wire to a leg of one of the supporting elements.

6. An appliance of the class described comprising a substantially rigid film-holding portion and a handle portion, the film-holding and handle portions being disposed in substantially parallel vertically spaced planes, the film-holding portion being an open frame of substantially rectangular contour, each side of the frame comprising elements which underlie and overlie the four margins of the film respectively, and each side of the frame having at least one pocket for the reception of corresponding edges of the film, said pockets having a concavely curved film-engaging surface and being so spaced and arranged that the film must be flexed in introducing it into the holder.

7. In an appliance for use in tray development of a cut film, said appliance comprising a substantially rigid film-holding portion and a handle, the film-holding portion including elements disposed to underlie and overlie the four margins of the film respectively, and film-positioning means having surfaces concavely curved in vertical planes and designed to engage the respective edges of the film, said positioning means being so designed and arranged as to tend to hold the film on all sides substantially in the mid-plane between said underlying and overlying elements, and mid-way between the upper and lower limits of said curved surfaces.

8. An apparatus for the class described comprising a substantially rigid film-holding portion and handle portion, the film-holding and handle portions being disposed in substantially parallel vertical spaced planes, the film-holding portion being an open frame of substantially rectangular contour, each side of the frame comprising elements which underlie the four margins of the film respectively, and each side of the frame having at least one pocket for the reception of an edge of the film.
